United States Patent

Des. 239,780
Patented May 4, 1976

239,780

LIGHTING FIXTURE

Ralph E. Paulson, 14802 Grevillea Ave.,
Lawndale, Calif. 90260

Filed Jan. 16, 1973, Ser. No. 324,196

Term of patent 14 years

Int. Cl. D26—05

U.S. Cl. D48—23 R

Fig. 6.

Fig. 4.

Fig. 5.

FIG. 1 is a front perspective view of a lighting fixture showing my new design;

FIG. 2 is an end view thereof on an enlarged scale, the undisclosed opposing end view is the same in appearance as the end view shown;

FIG. 3 is a fragmentary front side elevation view thereof, the undisclosed rear side elevation view is the same in appearance as the side shown;

FIG. 4 is a fragmentary top plan view thereof;

FIG. 5 is a fragmentary bottom view thereof; and

FIG. 6 is a fragmentary partial cross section of a front side elevation view of my new design.

FIGS. 2, 3, 4 and 5 are illustrated in fragmentary form for convenience of illustration only.

I claim:

The ornamental design for a lighting fixture, substantially as shown and described.
